CLYDE J. COLEMAN, OF NEW YORK, N. Y., ASSIGNOR TO ROCKAWAY AUTOMOBILE COMPANY, OF ROCKAWAY, NEW JERSEY, A CORPORATION OF NEW JERSEY.

INTERNAL-COMBUSTION MOTOR.

981,978.

Specification of Letters Patent. Patented Jan. 17, 1911.

Application filed February 18, 1901. Serial No. 47,893.

To all whom it may concern:

Be it known that I, CLYDE J. COLEMAN, a citizen of the United States, and a resident of the borough of Manhattan, in the 5 county of New York, city of New York, and State of New York, have invented new and useful Improvements in Internal-Combustion Motors, of which the following is a specification, reference being had to the accompanying drawings, forming part thereof.

My invention relates to internal combustion motors and particularly to internal combustion motors designed to operate at a very high speed.

My invention consists in the provision of 15 a compound compressor connected with an internal combustion motor whereby a high degree of compression of the motive fluid may be attained with a minimum expenditure of power in effecting such compression; in the provision of a storage tank for receiving and storing a reserve supply of compressed motive fluid, together with means whereby such motive fluid may be 20 employed in the motor when desired; in providing the motor with a rotary and a stationary member having turbine blades, the rotary member being exteriorly arranged; in providing the two members with 25 two sets of turbine blades and a combustion chamber between them; and in compounding these sets of turbine blades on both sides of the combustion chamber.

The objects of my invention are to provide for the rapid and continuous compression of a large quantity of motive fluid in 35 order that a high speed may be attained in the motor, and hence a high degree of efficiency obtained therefrom, while at the same time to provide that a minimum of power may be expended for effecting the compression; to provide an auxiliary or reserve supply of compressed motive fluid to be employed in first starting up the motor; to increase the efficiency of the motor while reducing its size and weight; to maintain a low temperature in the rotary member so that it may resist the great centrifugal force; and to balance the operation of the 45 motor, whereby steadiness of working and greater speed with proportionately less vibration are obtained.

My invention further consists in certain 50 details of construction and combination of parts as will hereinafter more fully appear,

and other advantages will be apparent from the more detailed description following.

I will now proceed to describe an internal combustion motor embodying my invention and will then point out the novel features in claims.

In the drawings which form a part of this specification; Figure 1 is a central longitudinal sectional elevation of an internal combustion motor embodying my invention. 60 Fig. 2, is a central transverse sectional view of the same, the plane of section being taken on the line 2—2 of Fig. 1. Fig. 3, is a detail transverse sectional view taken upon the plane of the line 3—3 of Fig. 1. Fig. 4, is a detail view in side elevation of one member of the motor.

In the present embodiment of my invention I provide a base plate 1 having standards 2 which support the opposite ends of 75 a stationary shaft 3.

Rotatably supported upon the stationary shaft is a rotary compound compressor 4. The said compressor has a plurality of compound cylinders, comprising outer initial 80 compression chambers 5, and inner compression chambers 6 of smaller diameter, and a plurality of compound reciprocating pistons for the cylinder, having heads 7 fitting the chambers 5 and smaller heads 8, fitting the 85 chambers 6. The pistons are connected by means of connecting rods 9 with a stationary wrist pin 10, supported by crank arms connecting to, or a part of, the stationary shaft 3.

When the compressor 4 rotates upon the stationary shaft 3 the pistons are caused to reciprocate and motive fluid is initially compressed in the outer chambers 5 of the cylinders and discharged from thence into the 95 inner chambers 6. The motive fluid is further compressed in the inner chambers and is then discharged into the central chamber 11 of the compressor, from whence it is delivered through a hollow portion of the stationary shaft into the combustion chamber of the motor. Motive fluid is delivered to the outer chambers 5 of the compressor cylinders through pipes or conduits 12 which connect with a receiving chamber 13, this receiving chamber being in direct communication with a carburetor 14.

The motor proper comprises two members, a stationary and a rotary member. The stationary member 15 is secured upon the sta- 110

tionary shaft 3 and is provided with two sets of directing vanes 16 radiating outwardly therefrom, and arranged upon opposite sides of a central combustion chamber 17. The rotary member 18 is secured at one end to the compressor and at the other end is rotatably mounted upon the stationary shaft, and is arranged exteriorly to the stationary member. This rotary member is provided with a plurality of radial turbine vanes 19, projecting inwardly, and arranged in proximity to the directing vanes of the stationary member 15.

At the center of the combustion chamber 17 is provided a burner 20. The burner consists of a number of apertures provided radially around the hub of the stationary member, and communicating through the hollow portion of the shaft 3 with the central chamber 11 of the compressor. Wire gauze is provided back of the apertures to prevent a possible back flashing of the flame from the combustion chamber into the interior of the burner.

25 The turbine vanes being arranged upon opposite sides of the central burner and combustion chamber, a balance of force and an equal distribution of power is insured. The vanes are further compounded, that is to say there are arranged on opposite sides of the combustion chamber successive rows of turbine impact vanes alternating with successive rows of turbine directing vanes. In this manner a high degree of efficiency is obtained.

It is my intention to operate the motor herein at a high rate of speed in order to obtain a high degree of efficiency. In order that it shall run at a high rate of speed 40 it is necessary to continuously compress a large quantity of motive fluid to a high degree so as to deliver a sufficient quantity of motive fluid to the motor. To this end a compound compressor is employed for the 45 reason that a higher degree of efficiency combined with small dimensions and weight of the parts and the use of a smaller amount of power is possible in a compressor of such type. With the compressor connected to rotate with the rotary member of the motor, it is essential that the parts should be small and light, otherwise centrifugal force would be liable to be generated to an unsafe extent, and vibration and wear would be excessive. 50 If motive fluid is employed at a high pressure, and a motor having turbine vanes is employed, it is essential to economical and efficient operation that the vanes should be compounded, otherwise the motive fluid 55 would be forced through the vanes without producing the most effective results, and a large percentage of its energy would be wasted. Hence I employ a compound compressor combined with a turbine motor having compound vanes and by such combina-

tion obtain an internal combustion motor of small size and exceedingly high efficiency.

In order to obtain a supply of compressed motive fluid when starting up the motor, I provide a storage tank 21 which is connected 70 to the central chamber 11 of the compressor through a pipe or conduit 22 and a hollow portion of the stationary shaft 3. While the compressor is working, motive fluid will be stored up in this storage tank under pressure, and will be retained therein by a check valve 23 which will operate to prevent the compressed fluid from returning along the pipe 22 until desired. Motive fluid is thus stored up under pressure which may be 80 utilized, after the motor has stopped and the pressure has run down therein, for the purpose of starting the motor up again. In order to use the compressed and stored motive fluid for such purpose I have provided a by-pass 24 around the check valve, and have provided therein a valve 25 which may be operated by hand or otherwise to permit the stored motive fluid from the tank 21 to discharge into the motor. The tank 90 is designed to store a sufficient quantity to start the rotation of the motor and to operate it until the compressor provides the normal and constant supply. During the operation of the motor the tank 21 will be 95 recharged and the valve 25 may be closed at once or it may be closed at any time after the compressor has commenced to supply motive fluid at a pressure greater than the pressure in the tank at that time, and before the motor has been again stopped. Preferably the valve 25 will be closed immediately the motor has commenced to run at full speed and pressure.

It is evident that various changes and modifications may be made in the construction shown and above particularly described within the spirit and scope of my invention.

What I claim and desire to secure by Letters Patent is:—

1. The combination with an internal combustion motor comprising two members, the one stationary and the other rotary, of a compressor comprising a plurality of compound cylinders connected to rotate with said rotary member, and having reciprocating pistons mounted therein and connected to a stationary wrist pin, each compressor being adapted to compress motive fluid for the motor.

2. A rotary internal combustion motor comprising two members, an inner stationary member and an outer rotary member rotatable about such stationary member, the inner member having two sets of power directing turbine blades and the outer member having two sets of power developing turbine blades, an enlarged combustion chamber located between the two sets of blades of the respective members, and means

- within the combustion chamber for effecting the combustion of the motive fluid.
3. A rotary internal combustion motor comprising two members, an inner stationary member and an outer rotary member rotatable about such stationary member, the inner member having two sets of power directing turbine blades and the outer member having two sets of power developing turbine blades, an enlarged combustion chamber located between the two sets of blades of the respective members, and means for effecting the combustion of the motive fluid within the combustion chamber, such means including an ignition device and a passage for the motive fluid within the stationary member and leading to said ignition device. 70
4. A rotary internal combustion motor comprising an inner stationary member and an outer rotary member rotatable about such inner member, each of said members having two sets of power developing turbine blades, a combustion chamber located inside the outer rotary member and outside the inner stationary member and between the two sets of turbine blades, and ignition means within said chamber. 75
5. A rotary internal combustion motor comprising an inner stationary member and an outer rotary member rotatable about such inner member, said members having two sets of compound turbine power developing blades, a combustion chamber located inside of the outer rotary member and outside the inner stationary member and between the two sets of blades, and ignition means within said chamber. 80
6. A rotary internal combustion motor comprising two members, an inner stationary member provided with two power developing sets of outwardly radiating directing vanes, an outer rotary member having two sets of inwardly radiating turbine vanes, and having a combustion chamber located inside the outer rotary member and outside the inner stationary member and between the pairs of sets of vanes of both the said members, and ignition means within said chamber. 85
7. The combination with a rotary internal combustion motor comprising two members, a stationary member and a rotary member, said members having two sets of power-developing turbine blades, and a combustion chamber between them and located outside the stationary member and within the rotary member and containing ignition means for the motive fluid, of a rotary compressor adapted to rotate with the rotary member of the motor, and to supply motive fluid under pressure thereto. 90
8. The combination with a rotary internal combustion motor comprising two members, a stationary member and a rotary member, said members having two sets of power-developing turbine blades, and a combustion chamber between them and located outside the stationary member and within the rotary member and containing ignition means for the motive fluid, of a compound compressor connected to revolve with the rotary member of the said motor, and to supply motive fluid under pressure thereto. 95
9. The combination with a rotary internal combustion motor comprising two members, a stationary member and a rotary member, said members having two power developing sets of compound turbine blades and a combustion chamber between the two said sets and located outside the stationary member and within the rotary member and containing ignition means for the motive fluid, of a compressor connected with said motor and adapted to supply motive fluid under pressure thereto. 100
10. The combination with a rotary internal combustion motor comprising two members, a stationary member and a rotary member, said members having two power developing sets of compounded turbine blades and a combustion chamber between the two said sets and located outside the stationary member and within the rotary member and containing ignition means for the motive fluid, of a rotary compressor adapted to rotate with the rotary member of said motor, and to supply motive fluid under pressure thereto. 105
11. The combination with a rotary internal combustion motor comprising two members, a stationary member and a rotary member, said members having two power developing sets of compounded turbine blades and including a combustion chamber between them and outside the stationary member and containing ignition means for the motive fluid, of a compound compressor adapted to revolve with the rotary member of the motor, and to supply motive fluid under pressure thereto. 110
12. A turbine internal combustion motor comprising an inner stationary member and an outer rotary member, the inner stationary member having outwardly radiating turbine vanes and the outer rotary member having inwardly radiating turbine vanes, such turbine vanes being arranged to present inclined faces to motive fluid moving in the general direction of the axis of rotation of the outer rotary member and a combustion chamber in proximity to such turbine vanes and outside the stationary member and containing ignition means for the motive fluid. 115
13. The turbine internal combustion motor comprising two members, an inner member and an outer rotary member, such means being rotatable relatively to each other and including a medial combustion chamber located outside the inner member and having ignition means therewithin, said combustion 120
14. The turbine internal combustion motor comprising two members, an inner member and an outer rotary member, such means being rotatable relatively to each other and including a medial combustion chamber located outside the inner member and having ignition means therewithin, said combustion 125
15. The turbine internal combustion motor comprising two members, an inner member and an outer rotary member, such means being rotatable relatively to each other and including a medial combustion chamber located outside the inner member and having ignition means therewithin, said combustion 130

- chamber being arranged to deliver the motive fluid along the general direction of the axis of rotation of the motor and each of such members having turbine vanes in two power developing sets, one set on each side of the combustion chamber, such turbine vanes being arranged to successively present inclined faces to the motive fluid moving in such general direction.
- 10 14. The combination with a turbine internal combustion motor, comprising two members, an inner stationary member and an outer rotary member, said members having compounded turbine vanes arranged to present inclined faces to motive fluid moving in the general direction of the axis of rotation of the turbine and the outer rotary member incasing the inner stationary member, a combustion chamber located outside the inner stationary member and within the said outer rotary member and containing ignition means for the motive fluid to said outer rotary member and adapted to supply motive fluid to such combustion chamber.
- 15 15. A rotary internal combustion motor comprising two members, an inner stationary member and an outer rotary member rotatable about such stationary member, said members having two sets of power developing turbine blades, a combustion chamber

located between the respective sets of turbine blades and outside the stationary member, said stationary member including means for discharging motive fluid in the combustion chamber, and ignition means within the 35 combustion chamber.

16. The combination with a rotary internal combustion motor comprising two members, a stationary member and a rotary member, said members having two sets of power 40 developing turbine blades and a combustion chamber between the respective sets of turbine blades, such chamber being located outside the stationary member and within the rotary member and having an unrestricted 45 opening leading to each of the sets of turbine blades, ignition means within said chamber, a compressor connected with the rotary member of said motor and arranged to revolve therewith upon the stationary member 50 of said motor, such compressor being adapted to supply motive fluid under pressure to the motor.

Signed at New York, N. Y., this 8th day of February, 1901.

CLYDE J. COLEMAN.
